UNITED STATES PATENT OFFICE

AUGUSTUS E. RICH, OF FALL RIVER, MASSACHUSETTS.

DEVICE FOR EMPTYING BOTTLES.

SPECIFICATION forming part of Letters Patent No. 289,447, dated December 4, 1883.

Application filed June 21, 1883. (No model.)

To all whom it may concern:

Be it known that I, AUGUSTUS E. RICH, of Fall River, county of Bristol, State of Massachusetts, have invented an Improvement in 5 Devices for Emptying Bottles, of which the following description, in connection with the accompanying drawings, is a specification, like letters on the drawings representing like parts.

10 My invention relates to a device for discharging the contents of bottles, especially those filled with aerated liquids, and is intended to be used in connection with a bottle having a stopper provided with a passage controlled by 15 a valve.

The discharging device consists, essentially, of a tube adapted to enter the said passage in the stopper and unseat the valve, thus permitting the liquid to escape and pass through 20 the tube, which may be withdrawn when a sufficient quantity of liquid has been discharged to allow the valve to close and retain the remainder of the liquid without escape of the gases therefrom.

25 The discharge-tube is preferably provided with a flange or projection, by which it may be forced into the passage in the stopper by the fingers of the operator, and it is also provided with a yielding washer, which serves to 30 pack the space between the tube and stopper, to prevent the escape of any liquid around the tube, the said washer also operating by its elasticity to withdraw the tube from the passage as soon as it is relieved from the pressure 35 of the fingers of the operator.

The discharging device is shown in this instance as constructed to operate with a bottle-stopper invented by me, for which Letters Patent No. 252,059 were granted June 10, 40 1882, to which reference may be had. The discharge-tube has lateral inlet-passages near the end which enters the stopper, to admit the liquid to the interior of the tube.

45 Figure 1 shows in longitudinal section a bottle and its stopper provided with a discharge-tube embodying this invention, and Fig. 2 a side elevation of the said discharge-tube.

The bottle *a* is provided with a stopper consisting of a metal cap, *b*, having a passage, *b'*, communicating with the interior of the bottle,

and a rubber or flexible packing, *c*, fitted around the said passage *b'* and entering the neck of the bottle, the said packing having connected with it by yielding arms *c'* a valve, 55 *d*, closing the inner end of the said passage *b'*, the said valve being held to its seat both by the elasticity of the arms *c'* and the pressure of the gases in the bottle. The said stopping device is more fully described in my former 60 patent, hereinbefore referred to, and consequently needs no further description here.

The discharging device consists, essentially, of a tube, *e*, of proper size to enter the passage *b'* of the stopper, and when forcibly pressed 65 into the said passage it unseats the valve *d*, to permit the liquid to escape. The lower end of the said tube is itself closed by the valve *d*, and in order to permit the liquid to enter and pass through the tube the latter is provided 70 with one or more inlet-passages, *2*, in its sides, they being shown in this instance as formed by slotting the end of the tube for a short distance. The discharge-tube *e* is provided with a yielding washer, *i*, (shown as a ball of soft 75 rubber,) which is prevented from longitudinal movement on the said tube by a flange, *m*. When the tube is forced into the stopper to unseat the valve *d*, as shown in Fig. 1, the washer *i* forms a tight packing between the 80 stopper and the exterior of the tube, to prevent the liquid from escaping through the passage *b'* around the tube. The flange or projection *m* facilitates the operation of pressing the tube *e* in the stopper; and the washer *i* by 85 its elasticity will automatically press the said tube out as soon as it is released by the operator, permitting the valve *d* to close. The bottle will be held in inverted position while the liquid is being withdrawn, so as to prevent the escape of the gases, and it will be seen that any desired amount may be withdrawn at any time without permitting the gas to escape from the liquid left in the bottle, so 90 that it will be kept in sparkling condition until all is withdrawn.

I claim—

1. As an improved article of manufacture, a discharging device for drawing the contents of a bottle having a stopper provided with a passage and valve, it consisting of a discharging-tube adapted to enter the said passage and

unseat the said valve, and means to pack the space between the said tube and stopper, substantially as described.

2. The discharge-tube provided with a projection, combined with the elastic washer surrounding the said tube, and engaged by the said projection to co-operate with a bottlestopper provided with a passage and valve, substantially as described.

10 3. The discharge-tube provided with a lateral inlet-passage and a flange or projection,

combined with the washer surrounding the said tube, and prevented from moving longitudinally thereon by the said flange, substantially as described.

In testimony whereof I have signed my name to this specification in the presence of two subscribing witnesses.

AUGUSTUS E. RICH.
